UNITED STATES PATENT OFFICE.

WILLIAM REMICH, OF SINKING SPRING, PENNSYLVANIA.

SHAFT AND THILL IRON.

No. 874,625.

Specification of Letters Patent.

Patented Dec. 24, 1907.

Application filed September 26, 1907. Serial No. 394,729.

To all whom it may concern:

Be it known that I, WILLIAM REMICH, a citizen of the United States, residing at Sinking Spring, in the county of Berks and State of Pennsylvania, have invented a new and useful Improvement in Shaft and Thill Irons, of which the following is a specification.

This invention is a new and improved construction of shaft and thill irons, the object 10 being to provide an exceedingly strong and durable connection between the axle and end of the shaft and which will entirely obviate the necessity of using curved or bent wood in the construction of shafts or thills.

15 Broadly speaking, the invention consists in the employment of a trussed metallic frame work one end thereof being adapted to receive the end of the shaft or thill and the other end having connection with the thill 20 coupling carried by the axle, the innermost portion being braced for the purpose of providing additional strength and the invention consists also in the employment of a supplemental diagonal brace to prevent lateral 25 strain.

The invention consists also in certain details of construction all of which will be fully described hereinafter and pointed out in the claims.

30 In the drawings forming a part of this specification, Figure 1 is a detail perspective view showing my improved form of shaft or thill iron connected to the rear end of the shaft or thill, a portion of the cross piece being also shown. Fig. 2 is a bottom plan view of the iron together with the rear end of the thill and adjacent end of the cross piece. Fig. 3 is a detail sectional view.

35 In the practical application of my invention I employ the usual or any approved construction of shaft or thill A being exactly alike and connected at their rear ends by means of a cross piece B, said connection being preferably made by means of a mortise and tenon joint. It will be noted that the 40 end of the shaft or thill is not curved downwardly as commonly done but connected to the rear end of the shaft or thill is a truss frame C comprising upper curved bar D and a lower straight bar E, said bars D and E being preferably constructed of a good quality of steel. The rear end of the shaft or thill A is inserted between the forward ends of the bars D and E and carriage bolts F serve to

securely fasten the parts together. It will 55 be noted that the upper and lower bars extend a considerable distance forwardly upon the upper and lower faces of the shaft or thill thereby providing a very firm connection between the truss frame and shafts. As before 60 stated the upper bar D is curved preferably in the arc of a circle and adjacent its rear and lower end it is bent or looped horizontally as shown at D' and the lower and rear end of the bar E is bent or looped horizontally as 65 shown at E' and it will be noted that the bend or loop D' is downwardly while the bend or loop E' is upwardly and furthermore the bend or loop E' fits within the bend of loop D', a sleeve or bearing being provided 70 through which the thill bolt can be passed and in order to maintain these bends in their proper positions I pass a short bolt G through the said bends as most clearly shown in Fig. 1.

75 For the purpose of bracing the truss frame, I employ a strut or bridge piece H which may be of wood or metal and which is held in position by means of a bolt H' passing through the upper and lower bars and the strut or bridge. In order to prevent lateral strain and also brace the connection between the end of shaft and cross piece, I employ an angular brace I, the horizontal member I' being bolted to the under side of the cross 80 piece while the oblique member I² extends down and passes into the bend or loop E' and is secured there by means of a bolt G which passes therethrough. A supplemental brace K extends across the angle formed 85 between the ends of the shaft and cross piece and it will be noted that this supplemental piece is secured in position by means of the bolts which serve to secure the main brace to the cross piece and the shaft irons to the 90 shaft. By means of a connection such as herein shown and described the shaft A can be quickly and easily detached whenever desired and another shaft inserted in its place. Furthermore in shipping the shafts, the iron 100 frames can be dismembered and packed into a very small space thereby saving a great deal of space during shipment and the parts can be quickly and easily assembled whenever desired.

105 A shaft connection construction as herein shown and described is exceedingly strong and durable and provides a very convenient

connection at the point where strength, durability and elasticity are most needed.

Having thus fully described my invention what I claim as new and desire to secure by 5 Letters Patent is:—

1. A shaft connection comprising the upper curved bar and the lower straight bar, the rear ends thereof being bent or looped and adapted to fit one within the other, means for fastening said bent or looped ends together, means for connecting forward ends to the shaft or thill, and the intermediate 10 strut or brace.
2. A shaft connection comprising the curved upper bar and the straight lower bar, the rear ends of said bars being bent or looped and adapted to fit one within the other, the intermediate brace connecting the upper and lower bars and the angular brace 15 having its rear end fastened within the bent

or looped ends of the upper and lower bars as specified.

3. The combination with a shaft and cross piece, of the upper curved bar bent downwardly at its rear end, the lower straight 20 bar bent upwardly at its rear end and fitting within the bend at the end of the upper bar, the intermediate strut or bridge piece, the angular brace having its rear end secured within the bend of the upper and lower bars, 25 and the horizontal member of said brace being connected to the bottom of the cross piece, and the supplemental brace connecting the shaft and cross piece and also the brace and bars together with bolts for fastening the said parts together as specified.

WILLIAM REMICH.
